UNITED STATES PATENT OFFICE.

EDWARD J. FROST, OF SPRINGFIELD, MASSACHUSETTS.

DESIGN FOR COLLARS AND CUFFS.

Specification forming part of Design No. 2,348, dated July 3, 1866.

To all whom it may concern:

Be it known that I, EDWARD J. FROST, of Springfield, Hampden county, Commonwealth of Massachusetts, have invented or produced a new and original Design for Collars, Cuffs, &c.; and I do hereby declare that the following is a full and exact description of the same.

This design, intended to be wrought upon a collar known as the "Fenian" collar, consists of a sprig of shamrock, arranged as is shown in the parts A and B in the drawing—that is, the same design being reversed so as to suit both parts of the article embossed.

I also wish to apply this design to cuffs and bosoms, and either print or emboss it, as may

be desired, and upon any material of which these articles may be composed, the design being arranged substantially as is shown in the drawing.

Now, having described my invention, what I wish to secure by Letters Patent, and claim as new, is—

A design for ornamenting collars, cuffs, and bosoms, representing a sprig of shamrock arranged substantially as shown and described.

EDWD. J. FROST.
